US00D964315S

(12) **United States Design Patent** (10) Patent No.: **US D964,315 S**
(45) Date of Patent: ** Sep. 20, 2022

(54) **HEADSET**

(71) Applicant: **EPOS Group A/S**, Ballerup (DK)

(72) Inventors: **Mohamad Essabar**, Ballerup (DK);
Peter Vestergaard Vaerum, Ballerup (DK)

(73) Assignee: **EPOS GROUP A/S**, Ballerup (DK)

(**) Term: **15 Years**

(21) Appl. No.: **29/764,689**

(22) Filed: **Dec. 31, 2020**

(30) **Foreign Application Priority Data**

Jul. 3, 2020 (EM) 008029953-0001
Jul. 3, 2020 (EM) 008029953-0002

(51) **LOC (13) Cl.** **14-01**

(52) **U.S. Cl.**

USPC **D14/205**

(58) **Field of Classification Search**

USPC D14/205, 223; D24/174; 128/864-866;

(57) **CLAIM**

The ornamental design for a headset, as shown and described.

DESCRIPTION

FIG. 1 is a front view of the headset;
FIG. 2 is a rear view thereof;
FIG. 3 is a top view thereof;
FIG. 4 is a bottom view thereof;
FIG. 5 is a left side view thereof;
FIG. 6 is a right side view thereof;
FIG. 7 is a perspective view thereof;
FIG. 8 is a front side view thereof;
FIG. 9 is a rear view thereof;
FIG. 10 is a top view thereof;
FIG. 11 is a bottom view thereof;
FIG. 12 is a left side view thereof;
FIG. 13 is a right side view thereof; and,
FIG. 14 is a perspective view thereof.

1 Claim, 14 Drawing Sheets
